UNITED STATES PATENT OFFICE.

JOHN J. McBRIDE, OF BAYONNE, NEW JERSEY, ASSIGNOR TO AMERICAN CAR AND FOUNDRY COMPANY, OF NEW YORK, N. Y., A CORPORATION OF NEW JERSEY.

BRAKE-BEAM SUPPORT.

Application filed July 12, 1926. Serial No. 121,879.

This invention relates to improvements in brake beam supports, reference being had to the accompanying drawings which illustrate the preferred form of the invention; though it is to be understood that the invention is not limited to the exact details of construction shown and described, as it is obvious that various modifications thereof within the scope of the claims will occur to persons skilled in the art.

In said drawings:

Fig. 1 is a fragmentary view of parts of a truck frame as seen with the truck "end on," the "spring plank" shown being in longitudinal section as indicated by the line 1—1 in Fig. 2, and the supports in cross-section;

Fig. 2 is a fragmentary plan view of the spring plank and the supports;

Fig. 3 shows a cross-section through the spring plank adjacent one of the supports, taken as indicated by the line 3—3 in Fig. 2, the support being shown partly broken away;

Fig. 4 is a fragmentary sectional view of the spring plank and a support, similar to Fig. 1 but on a larger scale, illustrating the installation or removal of a support.

My invention relates to brake beam supports and their mounting, and particularly emergency or safety supports (as they are termed), for preventing brake beams which may get loose from falling to the railway track and causing accidents. I aim not only to mount the emergency support in such a way that it will be secure when properly fastened, but also to guard against its being carelessly left insecurely fastened. In the form of embodiment here shown and described, my invention is in some aspects in the nature of an improvement of the construction shown and described in U. S. Patent 1,405,429, Feb. 7, 1922, to A. E. Ostrander.

The parts of the truck shown in the drawings include the car wheel 5, the truck bolster 6, the spring plank 7 with one of the bolster columns 8, and the brake lever 9. In the present instance, the spring plank 7 is of channel construction, with horizontal web 10 and upstanding flanges. The safety or emergency brake beam supports 12, 12 carried by the spring plank 7 project to either side thereof with an upward slope, in position to sustain the brake beams (not

shown) in case of accident to the brake rigging (not shown). Each of these supports 12, 12, may consist of an angle bar arranged with one flange flat against the lower side of the spring plank 7, and the other flange 13 turned downward. For the purpose of mounting the supports 12, 12, there are lugs or tongues 14 attached to the spring plank 7, offset laterally below its lower surface in parallelism therewith. The supports 12, 12 have their horizontal flanges engaged between the corresponding tongues 14 and the lower surface of the web 10. Such a tongue 14 may be formed integral with the spring plank web 10, by cutting or punching a portion thereof free along three sides and bending or joggling it outward adjacent its remaining attachment or "root," as shown at 15 in Figs. 1 and 4. In Fig. 2, two tongues 14, 14 are shown for each of the supports 12, 12.

As shown in the drawings, each tongue 14 not only engages the corresponding support 12 as above described, but also penetrates it, through an opening 16 slotted at the base of the depending angle bar flange 13. By its engagement in the opening 16, the tongue 14 prevents the support 12 from shifting in the direction of its own length, transversely of the spring plank 7. As here shown, each angle bar 12 "faces" the attached end 15 of each tongue 14 associated with it, so that the tongue penetrates the flange 13 near its own free end.

Disengagement of a support 12 from the corresponding tongues 14, 14, may be prevented by displacing a portion of the plank web 10 laterally, so as to engage the support 12 at one side. As shown in Figs. 1 and 4, the securing means thus employed consists of the free ends of the tongues 14 themselves, which are bent upward (or "back") towards the web 10 and into the opening left therein by the initial offsetting of the tongues, as shown at 17. This is done, of course, after the support 12 has been put in position and pushed home to the roots of the tongues 14, 14 with the latter straight, as shown in full lines in Fig. 4,—the bent position of the free tongue end being shown in dotted lines in Fig. 4.

Not only is such a mode of securing a support 12 against disengagement, by means of a portion of the spring plank web 10, very effective and reliable in itself, but it also

minimizes the danger of a support being left without proper fastening; because when the support is engaged with the tongues 14, 14 and pushed home in the manner indicated in Fig. 4, the entire absence of anything to prevent its disengagement by a simple reverse movement is so obtrusively obvious that the workman is not at all likely to neglect bending the ends of the tongues 14, 14 laterally, as already described. In the bolt-secured construction shown in the above-mentioned Ostrander Patent No. 1,405,429, on the other hand,—where the tongue of the spring plank web does not penetrate the support at all, but bolts through support and plank web are relied on to secure the support against disengagement,—it occasionally happens that the nuts are carelessly left off the bolts, which are then very likely to be jolted out of the holes and allow the support to become disengaged. Such failure to put the nuts on seems to be largely induced by the fact that the mere presence of the bolts in their holes does really,—so long as they remain there,—prevent disengagement of the support.

What is claimed is:

1. The combination of a truck part having a web, a laterally offset tongue attached thereto, and a brake beam support engaged between said part and said tongue, with a portion of the web displaced laterally to secure the support against disengagement.

2. The combination with a truck part and a laterally offset tongue attached thereto, of a brake beam support engaged between said part and said tongue and supported and penetrated by the latter, with means beyond the portion of the support penetrated by

said tongue for preventing disengagement 40 of said support.

3. The combination with a truck part having a web and a laterally offset tongue attached thereto, of a brake beam support engaged between said web and tongue and also penetrated by the latter.

4. The combination with a truck part and a laterally offset tongue attached thereto, of an angle bar brake beam support with one flange engaged between said part and the 50 tongue and the other flange penetrated by the latter.

5. The combination with a truck part and a laterally offset tongue attached thereto, of a brake beam support engaged between said part and said tongue, and also penetrated and secured against disengagement by the latter.

6. The combination of a truck part having a web, a laterally offset tongue formed from 60 said web, and an angle bar brake beam support having one flange engaged between said part and the tongue and the other flange penetrated by the latter; a portion of the web being bent laterally to secure the support against disengagement.

7. The combination with a truck part having a web and a laterally offset tongue formed from said web, of an angle bar brake beam support facing toward the root of said tongue with one flange engaged between the same and the web and the other flange apertured at its base and penetrated by the tongue, the tongue being bent back toward the web beyond said last-mentioned flange.

In witness whereof I have hereunto set my hand.

JOHN J. McBRIDE.
